UNITED STATES PATENT OFFICE.

FRANCIS I. DU PONT, OF WILMINGTON, DELAWARE, ASSIGNOR TO THE E. I. DU PONT DE NEMOURS POWDER COMPANY, OF WILMINGTON, DELAWARE, A CORPORATION OF NEW JERSEY.

GRAINING-ROLLS FOR GRAINING EXPLOSIVE POWDER.

993,353.

Specification of Letters Patent. Patented May 30, 1911.

Application filed February 13, 1909. Serial No. 477,554.

To all whom it may concern:

Be it known that I, FRANCIS I. DU PONT, a citizen of the United States, residing at Wilmington, county of New Castle, and 5 State of Delaware, have invented a new and useful Improvement in Graining-Rolls for Graining Explosive Powder, of which the following is a full, clear, and exact description, reference being had to the accompanying drawings, which form a part of this 10 specification.

Heretofore the construction of graining rolls has been quite complicated, consisting of independent cutters inset into the face of 15 the roll or drum, and of shape to cut the desired form of grain, and hence are quite difficult of precise and proper construction.

I provide my graining rolls along the length of the face of the roll with a plurality of circumferential grooves intersected by a plurality of longitudinal radial grooves. In each of these longitudinal grooves is placed a cutter bar having on its outer face cutters. These cutter bars have free ends 25 which rest in a circumferential groove in the face of an eccentric disk. In the revolution of the rolls, the cutter bars are given a vertical, or in and out movement, in the longitudinal grooves in the face of the 30 graining roll. The parts are so arranged that the cutting edges of the cutter bars coincide with the top of the circumferential grooves in the roll at the place where the powder strip is fed between the rolls 35 and coacts with the circumferential grooves to cut the powder grains to proper form, and the cutter bars are moved to the bottom of the grooves at the point where the scraper acts to clean the grains out. This 40 enables the cutting or graining surface of the graining rolls to be readily and simply formed. At the same time it enables the cutters to be moved to the surface for graining and below the surface for removing the 45 grain.

I will now describe the embodiment of my invention illustrated in the accompanying drawings and then point out the invention in the claims.

50 In the drawings: Figure 1 is a plan view

of my apparatus for graining explosive powder. Fig. 2 is an elevation of same partly in section. Fig. 3 is a section through same on line 3—3, Fig. 1. Fig. 4 is an enlarged longitudinal section through 55 one of the graining rolls. Fig. 5 is an end view partly in section. Fig. 6 is a face view of one of the eccentric disks taken as on line 6—6, Fig. 4. Fig. 7 is a plan view of one of the scrapers. Fig. 8 is an elevation of a cutter bar and Fig. 9 is a section through same on line 9—9. Fig. 10 is a 60 face view of the gear *f*, shaft *d*, arm *g*, lugs *t*, *t*, and screws *h*, and their relative position with respect to each other.

a is one graining roll, *b* the other graining roll mounted to revolve respectively with the shafts *c* and *d*. *e* is a gear on shaft *c*, and *f* is a gear on shaft *d*, the two gears intermeshing. The shaft *d* is driven 70 by any appropriate means, not shown, and the motion is transmitted through the gears *f* and *e* to shaft *c*. The gear *f* is loose on the shaft *d*. *g* is an arm keyed to shaft *d*. *t* are lugs on the gear *f*, through orifices 75 in which lugs, the set screws *h* pass. The arm *g* projects in line with the set screws *h*, the connection between the gear *f* and shaft *d* being through the arm *g*. By this arrangement the gear *f* has a movement upon 80 the shaft *d* the extent of which is controlled by the position of the set screws *h*.

The longitudinal surface of each graining roll *a* and *b* is provided with a series of circumferential grooves *i* and a series of 85 longitudinal radial grooves *j*.

k are the cutter bars. On each end of these bars is the cut away extension *l* of greater width than the cutter bar proper (see Fig. 9). The cutter bar proper is provided with the cutters *m*. The cut away extension *l*, at each end of cutter bars, rests in a circumferential groove *v* in the face of an eccentric disk *n*. The disks are mounted up on the bushing *p* which eccentrically 90 surrounds but does not revolve with the shaft *c'*. The cutter bars proper rest in the grooves *j*. As was stated, the extensions *l* are thicker or greater in cross section than the cutter bar proper, so that when all the 95 100

- cutter bars are inserted in the longitudinal grooves with their extensions in the groove in eccentric disks, the extensions contact with each other and thus fill up the groove.
- 5 *z* are the scraper bars, one secured to the housings of each graining roll. Each bar has on its edge the scrapers, *w*, equal in number to the circumferential grooves in its corresponding graining roll and supported in such a position that, in the rotation of the roll, the scrapers enter the circumferential grooves and clear the grains therefrom.
- The rotation of the roll through the 15 groove in eccentric disk *n* give to the cutter bars an out and in movement in their grooves with respect to the face of the graining roll. The eccentricity of disk *n* is so adjusted that the cutting edges or cutters of the cutter bars are brought outward 20 in line with the edges of the circumferential grooves in the rolls at the point of cutting or graining the powder strip, and draw them in, to allow the scrapers to act, in the 25 circumferential grooves.
- The connection of the gear *f* to its shaft enables the graining rolls to be properly adjusted with respect to each other.
- Having now fully described my invention, what I claim and desire to protect by Letters Patent is:
1. In an apparatus for graining explosive powder, in combination, graining rolls having circumferential and longitudinal grooves 35 in their faces, cutter bars, having cutting edges, in said radial longitudinal grooves, means adapted in the rotation of the rolls to move said cutter bars vertically and means to give one of said rolls a definite and limited rotary movement independent of the other.
  2. In an apparatus for graining explosive powder, in combination, graining rolls, each having circumferential and longitudinal 45 grooves in their faces, cutter bars, having cutting edges, in said radial longitudinal grooves, means adapted, in the rotation of the rolls, to move said cutter bars vertically, and a scraper bar having scrapers in line 50 with the circumferential grooves in the rolls at a point below the surface of the rolls.
  3. In an apparatus for graining explosive powder, in combination, graining rolls, shafts for said rolls, each of said rolls having circumferential and longitudinal grooves, cutter bars, having cutting edges, in said radial longitudinal grooves, disks eccentrically mounted, each of said disks having a circumferential groove, extensions from said 55 cutter bars resting in said disk groove and supporting said cutter bars, and scraper bars having scrapers in line with the circumferential grooves in the roll at a point below the surface of the roll.
  4. In an apparatus for graining explosive powder, in combination, graining rolls, shafts for said rolls, each of said rolls having circumferential and longitudinal grooves, cutter bars, having cutting edges, in said radial longitudinal grooves, disks eccentrically mounted, each of said disks having a circumferential groove, extensions from said cutter bars resting in said disk groove and supporting said cutter bars, the extensions of said cutter bars resting in said groove 75 being thicker than the main portion of the cutter bars.
  5. In an apparatus for graining explosive powder, in combination, graining rolls, shafts for said rolls, each of said rolls having circumferential and longitudinal grooves, cutter bars, having cutting edges, in said radial longitudinal grooves, disks eccentrically mounted, each of said disks having a circumferential groove, extensions from said cutter bars, resting in said disk groove and supporting said cutter bars, the extensions of said cutter bars resting in said groove 85 being thicker than the main portion of the cutter bars, and a scraper bar having scrapers in line with the circumferential grooves in the roll at a point below the surface of the roll.
  6. In an apparatus for graining explosive powders, in combination, a pair of graining rolls, cutter bars in the face of said rolls, a shaft for each roll, intermeshing gears carried by the respective shafts, one of said gears being fixed to its shaft, the other gear being loose on its shaft, an adjustable device 100 carried by said loose gear, and a projection carried by and rotating with the gear shaft adapted to strike said adjustable device to drive said gear.
  7. In an apparatus for graining explosive powder, in combination, a pair of graining rolls, a shaft for each roll, a gear upon each shaft, said gears intermeshing, one of said gears being fixed on its shaft, and the other gear loose on its shaft, a shaft driving member carried by and rotating with said shaft and adjustable connection between said loose gear and the said shaft driving member whereby said loose gear is adapted to have a limited rotary movement upon its shaft.
  8. In an apparatus for graining explosive powder, in combination, a pair of graining rolls, a shaft for each roll, a gear upon each shaft, said gears intermeshing, one of said gears being fixed on its shaft, an arm on the other shaft, lugs on said last mentioned shaft gear, and adjusting screws passing through said lugs in line with said arm.
  9. In an apparatus for graining explosive powder, in combination, a pair of graining rolls, a shaft for each roll, a gear upon each shaft, said gears intermeshing, one of said gears being fixed on its shaft, and the other

gear loose on its shaft, and a stop on said gear making driving connection with the shaft at the limits of the independent rotary movement of the loose gear on its shaft,
5 said stop being adjustable for regulating the extent of said rotary movement of the loose gear upon its shaft.

In testimony of which invention, I have hereunto set my hand, at Wilmington, Del., on this tenth day of February, 1909.

FRANCIS I. DU PONT.
